GLUE DISPENSING GUN

Morris Gary Grossman, Wyckoff, N.J., assignor to Cooper Industries, Inc., Houston, Tex.

Filed Apr. 7, 1971, Ser. No. 132,255

Term of patent 14 years

Int. Cl. D8—05

U.S. Cl. D8—30

FIG. 1 is a side elevation of a glue dispensing gun embodying my new design, the opposite side being the same;

FIG. 2 is a top plan view thereof;

FIG. 3 is a bottom view thereof;

FIG. 4 is a front elevation thereof; and

FIG. 5 is a rear elevation thereof.

I claim:

The ornamental design for a glue dispensing gun, as shown and described.
